UNITED STATES PATENT OFFICE.

GEORGE W. MIX, OF BATAVIA, NEW YORK.

FEEDING DEVICE.

1,071,941.

Specification of Letters Patent.

Patented Sept. 2, 1913.

Application filed January 29, 1913. Serial No. 744,922.

To all whom it may concern:

Be it known that I, GEORGE W. Mix, a citizen of the United States, residing at Batavia, in the county of Genesee and State 5 of New York, have invented new and useful Improvements in Feeding Devices, of which the following is a specification.

This invention relates to a feeding device which is more particularly designed for 10 feeding beans or the like from a source of supply to one or more endless aprons upon which the beans are spread out and picked over by operatives for the purpose of separating the beans of good quality or large 15 size from those of inferior quality or small size.

It is the object of this invention to produce a feeding device for this purpose which is simple and inexpensive in construction and which will reliably and uniformly feed the beans to the sorting apron 20 without liability of clogging the machine and without consuming an undue amount of power.

25 In the accompanying drawings consisting of 2 sheets: Figure 1 is a side elevation of my improved feeding device. Fig. 2 is an end elevation thereof. Fig. 3 is a vertical longitudinal section taken in line 3—3, Fig. 30 2. Fig. 4 is a vertical transverse section taken in line 4—4, Fig. 3. Fig. 5 is a bottom plan view of the machine. Fig. 6 is a horizontal section taken in line 6—6, Fig. 3 and looking downwardly. Fig. 7 is a horizontal section taken in line 7—7, Fig. 3, 35 looking upwardly.

Similar characters of reference indicate corresponding parts throughout the several views.

40 As shown in the drawings, my improved feeding device is organized for feeding beans from a common source of supply to two sorting aprons 1, 1 which are arranged on opposite sides of the feed device but it is to be understood that my invention is applicable to a feeding device of this character 45 which supplies beans to a single sorting apron as well as to a plurality of such aprons. In the preferred arrangement of 50 these sorting aprons the receiving turns thereof pass around receiving rollers 2, 2 which are mounted on shafts 3, 3 and these rollers are turned in the direction for moving the upper stretches of the sorting aprons 55 in opposite directions away from the feeding device.

The feeding device is arranged between the two receiving rollers of the aprons and in its general organization the same comprises an upper supply chamber 4 which 60 communicates at its top with a supply tube or collar 5 to which the beans are delivered from a source of supply by any suitable means, and two delivery chambers 6, 6 arranged on opposite sides of the lower part 65 of the supply chamber. These chambers are made up partly by two upright longitudinal side plates 7, 7 which form the longitudinal side walls of these chambers, a horizontal top plate 8 extending transversely across the upper edges of the side plates and connected at its opposite longitudinal edges with the adjacent upper edges of the side plates and formed integrally with the supply tube 5, a bottom plate 9 arranged 70 transversely between the side plates and forming the bottom of the supply chamber and the delivery chambers and also inclining from its central part laterally in opposite directions, and upright end plates 10 75 arranged transversely between the corresponding lower parts of the upright edges of the side plates so as to form the outer end walls of the delivery chambers and connected at their opposite ends with the respective side walls. Each of the end walls of the delivery chambers is arranged at right angles to the adjacent inclined portion of the bottom plate and projects partly above this bottom plate and partly below the same 80 and is provided at its upper edge with a laterally projecting inclined delivery flange or guide lip 40 which overhangs the receiving portion of the adjacent sorting apron, 85 as shown in Figs. 1 and 3.

90 The opposite transverse walls of the supply chamber are made up of two vertically movable gates 11, 11 each of which is preferably constructed of a sheet of metal and guided at its opposite vertical edges in 95 guideways 12 formed on the adjacent parts of the inner sides of the side plates so that upon raising or lowering these gates more or less a passageway of varying capacity 100 may be formed between the lower edge of the same and the bottom plate through which the beans may pass from the supply chamber to the respective delivery chamber or these gates may be lowered into engagement with said bottom plate, thereby permitting of regulating the flow of beans from 105 the supply chamber to the respective de-

livery chamber or stopping the flow altogether. Various means may be employed for adjusting each of these gates, the means which are shown in the drawings being suitable and preferred and comprising a transverse spring adjusting rod 13 arranged along the outer side of the respective gate and passing with its central part through a loop 14 formed centrally on the outer side 5 of the gate and arranged at its rear end in an opening 15 formed in the adjacent edge portion of one of the side plates while its front end engages in one or another of a vertical row of notches 16 formed in the 10 upright edge of the adjacent edge of the other side plate. By arranging the rear end of the adjusting rod 13 in the opening 15 of one of the side plates, a fulcrum is formed for this rod which permits the front end 15 thereof to be raised or lowered together with the gate connected therewith and by engaging the free front end of this rod with one or the other notches 16 the gate may be held in various adjusting positions according 20 to the amount of opening or area of passageway required to supply the desired quantity of beans. By constructing the adjusting rod of spring material its front end is held yieldingly in engagement with the 25 respective notch 16 with which it is interlocked. This construction of gate adjusting device is exceedingly simple and inexpensive, the same can be easily operated and is not liable to get out of order.

30 35 The opposite transverse edges of the bottom plate are separated by an intervening slot, space or passageway 17 from the adjacent transverse outer walls of the delivery chambers, and in each of these openings or 40 slots a feed plunger reciprocates vertically for the purpose of intermittently lifting a charge of beans or the like from the lower part of the respective delivery chamber to a point above the upper edge of the adjacent 45 end wall so as to permit the beans thus lifted by the plunger to slide off from the latter and over the guide flange on to the companion sorting apron. Each of these plungers reciprocates vertically in a path or line 50 which is arranged parallel with the inclined end wall of the delivery chamber and at right angles to the adjacent inclined bottom portion of the delivery chamber. Each plunger is constructed of substantially 55 L-shaped form in vertical cross section and comprises an upper nearly horizontal lifting plate 18 arranged parallel with the adjacent part of the bottom plate and an inner nearly vertical cut-off plate 19 extending down- 60 wardly from the inner edge of the lifting plate and arranged at right angles to the latter or parallel with the adjacent transverse end wall. The plunger may be guided in its vertically reciprocating movement in 65 any suitable manner but preferably by en-

gagement of the outer edge of the lifting plate with the inner side of the adjacent end wall and by engagement of the inner side of the cut-off plate with inclined guide ribs or flanges 20 arranged on the adjacent parts of the side plates, as shown in Figs. 3 and 7. The plungers are held in proper engagement with the guiding surfaces and prevented from tipping out of alignment by means of guide ribs 21 arranged vertically 70 on the outer side of the cut-off plate and below the lifting plate and engaging their outer edges with the inner side of the end walls, as shown in Figs. 3, 5 and 7.

In the lowermost position of each feeding plunger the upper surface of the lifting plate thereof is arranged flush with the adjacent part of the bottom plate or substantially so, as shown at the left hand side of Fig. 3, in which position of this plunger 80 the beans escaping from the supply chamber past the underside of the gate are free to flow over the adjacent part of the bottom plate and upon the respective lifting plate and against the upper part of the adjacent 85 end wall. As the plunger is moved upwardly until it reaches the upper end of its stroke the upper surface of the lifting plate is arranged flush, or substantially so, with the upper edge of the adjacent end wall, 90 and during this movement the beans resting on top of the lifting plate are raised out of the delivery chamber and permitted to spill over the guide lip or flange onto the sorting apron while the beans in rear of 95 the plunger are held back by the cut-off plate thereof, this position of the plunger being indicated at the right hand side of Fig. 3. As the plunger again descends into its lowermost position the beans in the delivery chamber again flow over the upper end of the plunger preparatory to being 100 lifted by the latter over the adjacent end wall as before described.

Various means may be employed for imparting a reciprocating movement to the plungers but those shown in the drawings are preferred and constructed as follows: 110 22, 22 represent two rotary driving shafts arranged horizontally and transversely in the lower part of the machine but axially out of line with each other, these shafts being arranged below the respective plungers and on opposite sides of the longitudinal center of the side plates. One of these 115 shafts is journaled in a horizontal transverse bearing 23 arranged on the inner lower part of one of the side plates and extending from the respective side plate inwardly toward the central part of the machine while 120 the other shaft is similarly journaled in a horizontal transverse bearing 23 arranged on the inner side of the lower part of the other side plate and extending from the respective side plate to the central part of 125 130

the machine, so that these two bearings are parallel with each other but axially out of line and project inwardly in opposite directions from the respective side plates. At 5 its inner side each of the driving shafts is provided with a crank or arm 24 which carries a wrist pin 25 at its outer end. 26, 26 represent two connecting rods each of which is provided at its lower end with an 10 eye 27 which is confined on the wrist pin of one of the crank arms by means of a cotter pin 28 while its upper end is provided with an eye 29 which is arranged in a notch or recess 30 in the lower edge of the 15 cut-off plate of the adjacent plunger and engages with a horizontal pivot pin 31 arranged on the cut-off plate at one of the upright edges or walls of the said notch and projecting in the same direction as the 20 wrist pin of the crank arm. These means of connecting the plungers with the crank arm are exceedingly simple and inexpensive, the same are not liable to become deranged and can easily be assembled as well as dis- 25 membered for inspection or repairs inasmuch as each connecting rod when held on the wrist pin by the cotter pin is also confined upon the pivot pin of the plunger, as shown in Fig. 4.

30 Motion may be transmitted to the driving shaft and to the shafts of the sorting aprons in any suitable manner, for instance each driving shaft may be provided with a pulley 32 which receives a belt 33 connected to a 35 prime mover and each sorting apron shaft may be turned from the companion driving shaft by means of a belt 34 passing around pulleys 35, 36 secured to the companion driving shaft and apron roller shaft, as 40 shown for instance in Figs. 1, 2 and 5.

By providing a separate driving device for each feeding plunger and sorting apron the feeding of the beans to each of the sorting aprons may be controlled or stopped al- 45 together independently of the other feeding means and sorting apron, thereby permitting both of the feeding plungers and sorting aprons to be operated simultaneously and also permitting one of the feeding plun- 50 gers and sorting aprons to be stopped while the other feeding plunger and sorting apron continues to operate. This feeding device can therefore be readily adapted to the various conditions which are encountered in 55 actual practice to suit the speed or skill of

the operators who are sorting the beans or other material which is being picked over and to permit of temporarily stopping the sorting operation on one apron without interfering with this operation on the other 60 apron.

Owing to the simplicity of the construction of this feeding device the same can be produced at low cost and as the same contains no delicate parts there is little liability 65 of getting the same out of order. Furthermore, all of the passages through which the beans pass in this feeding device are wide and not liable to become clogged with beans and whenever it becomes necessary to change 70 from picking beans to picking another like material this can be quickly and easily effected inasmuch as all parts of this feeding device are readily accessible for removing any beans or like material from the cham- 75 bers before beginning the sorting of another material.

By providing each of the side plates of the supply and delivery chambers with an inwardly projecting bearing for a driving 80 shaft arranged on one side of the longitudinal center of these plates these bearings and the shafts journaled in the same will not interfere with each other and it also renders it possible to easily assemble or dismember 85 each of these shafts without interference with the other shaft, and it also permits of making both of the side plates and their bearings from the same pattern.

I claim as my invention:

A feed device comprising a delivery cham- 90 ber having two side walls, a bottom, and an outer end wall projecting above the bottom and separated by an intervening slot, a feed plunger reciprocating vertically in said slot 95 and having an upper lifting plate, an inner cut-off plate depending from the inner edge of the lifting plate, and guide flanges ar- 100 ranged on the outer side of the cut-off plate and underside of the lifting plate and en- gaging with the inner side of said end wall, and guide flanges arranged on said side walls and engaging with the inner side of 105 said cut-off plate.

Witness my hand this 24th day of Jan- 105
uary, 1913.
